(57) **CLAIM**

The ornamental design for a mooring device, as shown.

DESCRIPTION

FIG. 1 is an isometric view of the mooring device of the present invention;

FIG. 2 is a top view of the invention;

FIG. 3 is a bottom view of the invention;

FIG. 4 is a side view of the invention, as seen from the right side of FIG. 6;

FIG. 5 is a side view of the invention, as seen from the left side of FIG. 6; and,

FIG. 6 is a front view of the invention.

1 Claim, 6 Drawing Sheets
